UNITED STATES PATENT OFFICE.

GEORGE W. HILL, OF NEW YORK, N. Y., ASSIGNOR TO AMERICAN TOBACCO COMPANY,
A CORPORATION OF NEW JERSEY.

CIGARETTE-PACKAGE

1,396,749.

Specification of Letters Patent. Patented Nov. 15, 1921.

Application filed August 4, 1916. Serial No. 113,091.

To all whom it may concern:

Be it known that I, GEORGE W. HILL, a citizen of the United States, residing at New York city, in the county of New York and State of New York, have invented certain new and useful Improvements in Cigarette-Packages, of which the following is a specification.

This invention relates to certain novel and useful improvements in the packaging of cigarettes, little cigars and the like, in the present instance the invention being shown and described as a cigarette package.

Heretofore it has been the general practice to resort to two methods of packaging cigarettes, that is to say, the boxing and wrapping.

When the package is to embrace a relatively small number of cigarettes, ten for instance, they are usually arranged in one or two rows and are incased in a box of comparatively stiff material, such as card-board, box-board and the like, to prevent the individual cigarettes being broken or otherwise damaged. These card-board boxes are of various construction and design, and are more or less cumbersome and inconvenient, in addition to affording but a limited amount of protection to the contents. On the other hand, where a package is to embody such a relatively large number of cigarettes that it is inadvisable to use boxes for casing the same, it is the custom to envelop the cigarettes in a wrapper or cup-shaped

35 container, which is made of flexible, pliable material, such as paper, or a combination of paper and tin-foil. As the cigarettes in such case are arranged in a multiplicity of relatively short rows or layers in the package, or are bunched together, the natural thickness or bulk of the contiguously arranged cigarettes, coupled with the soft wrapper, constitutes a sufficient protection, under certain conditions, such for instance 45 so long as a package remains intact and contains substantially the original number of cigarettes.

This soft package, however, is of such bulk that it is inconvenient to carry about in the pocket, causing a bulging of the latter, and in addition to this, when a few of the cigarettes have been withdrawn from the casing or wrapper, so as to reduce the number of cigarettes remaining therein, the 55 wrapper is liable to collapse with the conse-

quent possibility of breaking or bending the cigarettes.

In the present instance it is my purpose to provide a cigarette package which will embody all of the advantages of both the box and the wrapper type of packages, and yet will be free from the inherent disadvantages thereof, such as have been above recited.

Still a further object of my invention is to provide a cigarette package which will be of sufficient stability and strength to adequately protect the contents, irrespective of the fact of whether the package contains its maximum or minimum number of cigarettes.

Furthermore, I propose to provide a package which will present a neat, attractive appearance, which may be readily and conveniently carried about in the pocket without bulging the latter, which may be readily manipulated to provide access to the cigarettes which will protect the latter from atmospheric changes, and from the entry of dirt, and other foreign substances, and which may be made up and marketed at a relatively low cost.

With the above recited objects, and others of a similar nature in view, my invention consists in the construction, combination and arrangement of parts set forth and falling within the scope of the appended claims.

In the accompanying drawings,

Figure 1 is a plan view of a blank of card-board or the like, adapted to be folded to constitute a case in which the cigarettes are initially packed.

Fig. 2 is a perspective view showing the cigarettes packed in the card-board case.

Fig. 3 is a perspective view showing the case in position to have the composite wrapping sheet applied thereto.

Fig. 4 is a plan view of a blank or sheet, from which the cover or pouch section of the package is made.

Fig. 5 is a perspective view of the complete outer cover or pouch portion of the package.

Fig. 6 is a perspective view of the completely wrapped and sealed cigarette package embodying my invention.

Fig. 7 is a vertical sectional view taken through the package, shown in Fig. 6.

The cigarette package forming the sub-

ject matter of this invention embraces, in the present instance, three principal sections or parts, that is to say, an inner box-like casing A, of card-board, box-board or other like material in which the cigarettes are initially packed in row or rows, a wrapper sheet B which is preferably in the nature of a composite sheet of paper and tin-foil, and in which sheet the casing A that contains cigarettes is adapted to be wrapped, and an outer cover preferably of pouch-like form which may be composed of suitable paper, leather, fabric or any desired material which possesses the requisite degree of flexibility and which may be ornamented or printed to suit the individual taste of manufacturer or merchant.

The inner, or card-board casing A, is preferably made from a blank, such as is shown in Fig. 1, comprising a rectangular body section 1, having the side wings 2 defined by the vertical score lines 3. The blank is also scored along the transverse lines 4, 5 and 6. In folding the blank to form the box, it is bent transversely on the lines 4 and 5 to constitute the bottom wall 7, which hingedly unites the back wall 8 with the front wall 9, while the sides of the casing are formed by the wings 2—2 after the blank has been folded or bent on the lines 3—3. Normally the front wall 9 of the casing A is of the same dimensions or area as the back wall 8, and when the cigarettes are packed in the casing, they are confined between these walls 8 and 9. When the package is in use, as by the customer, the front wall 9 may be folded or bent back on the score line 6 to expose the upper end portions of the cigarettes, such cigarettes being shown as D, with such upper end portions indicated by d. If desired, this section of the front wall formed by a folding or bending on the line 6, and which section is indicated at 9', may be entirely torn or severed from the main portion of the top.

After packing as above described, the casing A containing the cigarettes is preferably placed upon the central portion of a composite sheet, B, as is shown in Fig. 3, this sheet preferably comprising an outer layer of foil shown at 10, and an inner sheet of relatively thin paper shown at 11. If desired, the lining sheet of paper shown at 11 may be united to the foil sheet by thin strips or lines of adhesive shown at 12.

The opposite end portions of the composite sheet, B, are now folded over upon the top face of the case A, and into overlapping relation to wrap the casing, as will be readily understood, and as the composite sheet is of relatively greater width than the card-board casing, the extending marginal edges of the sheet are tucked in or lapped over as shown at 11' in Fig. 6, so that the casing A will be completely wrapped in the composite sheet.

At this stage, the package is completed by the application of an outer cover which is preferably of pouch-like form, and is made from a rectangular blank such as shown in Fig. 4. This blank has an adhesive applied to one of the shorter edges, as shown at 13, and to one of the adjacent longer edges thereof as shown at 14.

The casing A containing the cigarettes and now wrapped in the composite sheet, B, is placed upon the intermediate portion of this blank shown in the Fig. 4 and the two projecting portions of the blank brought into overlapping relations at one face of the package and united or joined along the seam 15 by adhesive 13. The bottom of the cover or pouch is then formed by tucking in the corners, as shown at 16, and folding inward the bottom edges 17, the latter being united by the adhesive 14.

The cigarette package is now of itself complete, but if desired a suitable band label or the like shown at 18 in Fig. 6, may be applied.

From the above description, taken in connection with the accompanying drawings, the construction and manner of preparing my improved package will be readily understood.

It will be noted that in the present instance, I have shown a single row of cigarettes D, but it will be understood that the package may contain a plurality of rows if desired. It will further be seen, that where the cigarettes are packed in but one or two rows, the card-board casing will protect the same against breakage owing to its inherent stiffness, and at the same time the wrapping sheet, B, and the pouch-like cover therefor, insure additional protection especially 105 against moisture and the like, and will also add to the appearance of the package when it is offered for sale.

Furthermore, I provide an inexpensive package, and one which may be readily and conveniently manipulated to afford access to the cigarettes, inasmuch as the card-board casing is formed from a single blank cut in an exceedingly simple manner to provide a box-like receptacle for the cigarettes, having 110 a bottom wall, two side walls, a hinged uniting wall, and a top wall, the end of the box opposite the hinged uniting wall being permanently open. If desired, the purchaser of the package may remove the pouch-like 115 cover and the wrapper sheet, and slip the card-board casing containing the cigarettes into a jacket or pouch especially adapted and prepared for this purpose, and which pouch forms the subject matter of a separate application.

While I have herein shown and described one particular embodiment of my invention, I wish it to be understood that I do not confine myself to all the precise details of con- 130

struction herein set forth by way of illustration, as modification and variation may be made without departing from the spirit of the invention or exceeding the scope of 5 the appended claims.

What I claim is—

1. A cigarette package comprising an inner casing of relatively stiff material having a permanently open end and in which 10 the cigarettes are initially packed, an intermediate wrapper sheet of relatively flexible material completely enveloping the inner cigarette-containing casing, and an outer flexible pouch-like cover receiving the 15 wrapper casing, said pouch-like cover also having a permanently open end through which the adjacent portion of the wrapper casing is exposed.

2. A cigarette package comprising an 20 inner casing formed from a single sheet of relatively stiff material and comprising a box-like casing adapted to have the cigarettes initially packed therein, said box-like member comprising a back wall, side walls, a 25 front wall, and an integral end wall hingedly uniting the front wall and the back wall, one end of the casing being permanently open, an intermediate composite 30 wrapper sheet of paper and metallic foil of greater width than the casing and wrapped about and completely enveloping the latter, and a flexible pouch-like cover formed from 35 a single sheet of material adapted to receive and removably contain the wrapped casing, and also having a permanently open end.

3. A cigarette package comprising a box-

like casing adapted to have the cigarettes packed therein, said casing having a back wall and the side walls integral therewith, and a front wall provided with a bendable 40 flap section and an end wall hingedly uniting the front wall and the back wall, thus forming a structure to resist bending and protecting the cigarettes when carried by the user and having a permanently open end, 45 a flexible composite sheet of greater width than the casing wrapped about and enveloping the latter, and a pouch-like cover formed from a single sheet of flexible material receiving the wrapped casing, such pouch-like 50 cover having a permanently open end.

4. A cigarette package comprising a box-like holder of relatively stiff material permanently open at one end and having a side wall thereof transversely scored to permit 55 the upper portion thereof adjacent the permanent opening to be folded outwardly, a flexible wrapper sheet folded about said holder to completely cover the same, and an outer casing of readily foldable material 60 permanently open at the end corresponding to the open end of the inner holder, and a narrow band around the open end of the outer casing to prevent separation of the parts until ruptured. 65

In testimony whereof I affix my signature in the presence of two witnesses.

GEORGE W. HILL.
